DECORATIVE CORD

Edward Philip Franke, Baltimore, Md.

Application October 5, 1935, Serial No. 43,733

8 Claims. (Cl. 117—60)

This invention relates in general to cordage and in particular to an improved decorative tying cord and to correlated improvements in the method of producing the same.

5 Decorative tying cords comprising a plurality of twisted fibrous strands which are now in use for various purposes have, among others, the important defect that when such cords are cut the ends tend to untwist, whereby the decorative 10 character of the cord is seriously impaired. Furthermore, when one of the strands of the cord consists of a strip of tinsel, the sharp edges of the tinsel strip tend to cut into the fibrous strands, producing a roughened surface and weakening the 15 strength of the cord at such points.

It is, therefore, the principal object of the present invention to provide an improved decorative tying cord in which certain elements are so combined as to resist disintegration when severed 20 and, at the same time, to offer a uniform tensile strength which cannot be impaired by bending or tying.

It is a specific object of the invention to provide a tying cord of decorative character formed 25 of a core of flexible, non-fibrous material and a decorative element encircling the core without de-forming or weakening the core.

Other objects of the invention will in part be obvious and will in part appear hereinafter.

30 According to the invention, a tying cord is formed of a twisted strip of flexible, non-fibrous material about which a relatively flat, thin strand having a metallic appearance, preferably a metal strip having rounded edges, is spirally wound in 35 open coils in the same direction as that in which the underlying strip of non-fibrous material is twisted.

For a more complete understanding of the nature and objects of the invention reference 40 should be had to the accompanying drawing, in which

Figure 1 is a view of a tying cord constructed in accordance with a simple embodiment of the invention, in which the cord comprises a core 1 of non-fibrous material and a tinsel strip 2 spirally wound about the core 1 in open coils.

Figure 2 is a view of a tying cord constructed in accordance with another embodiment of the invention, in which the tinsel strip 2' is itself 50 twisted before being spirally wound about the core 1.

The core comprises a substantially cylindrical cord formed by twisting one or more strips of any suitable, flexible, non-fibrous material, such, 55 for example, as cellulose hydrate; cellulose deriv-

atives such as cellulose esters, cellulose ethers, cellulose oxy-ethers; gelatine; casein, and other synthetic plastics. These materials may be colored or uncolored, transparent or opaque.

In the preferred embodiment of the invention, 5 the strip of non-fibrous material is given not more than 10 twists per foot of cord length, thus retaining to a substantial degree the flexibility characteristic of the non-fibrous material. If desired, the non-fibrous material may be plasticized 10 with any suitable plasticizer such as is known in the art, with the object of still further increasing the flexibility of the cord.

The metallic strand which is spirally wound about the core may comprise a metal wire or a 15 narrow strip of metal such as is commonly called "tinsel". The tinsel is formed preferably by flattening a fine metal wire, since this method gives a strip having rounded edges and avoids the sharp edges produced by cutting a sheet of thin 20 metal into narrow strips. In another embodiment the metallic strand comprises a narrow strip of flexible material covered on one or both sides with a metallic coating, such, for example, as a strip of transparent cellulose having on one side a metallic 25 coating formed by cathode sputtering of a metal. The metallic strand preferably contrasts in color with the core about which it is wound and may be embossed, crinkled, creped or otherwise surface roughened so as to reflect light from 30 a multiplicity of facets and thus enhance the decorative effect. For example, the metallic strand 2 may be embossed with a plurality of raised points 3 as shown in Fig. 1. Or the strand 2' may be crinkled to produce a multiplicity of 35 fine lines 4, as shown in Fig. 2. As may be seen from the drawing, the metallic strand is wound about the core in open coils in such manner that the non-fibrous material comprising the core is visible between the open coils of the strand. 40

The highly decorative character of the cord, due not only to the contrast in color between the core and the encircling strand, but more particularly to the glossy sheen and the metallic luster of those respective elements, may be still further enhanced if, as illustrated in Figure 2, the metallic strand is itself twisted before being wound about the core. Such preliminary twisting provides the metallic strand with a multiplicity of facets which reflect light with a scintillating effect. 45

In view of the known characteristics exhibited by cellulosic or similar non-fibrous material when twisted, it is obvious that a cord constructed of 50 55 60

the elements and in the manner above described will, while remaining perfectly flexible, retain its shape without deformation, loosening or disintegration where tied or severed. Furthermore, the 5 metallic strand, in the preferred embodiment, has rounded edges and the material composing the core is extremely tough and resistant to any cutting action, hence the tensile strength of the cord remains uniform at every point no matter how the 10 cord is used.

Since certain modifications in the article of the invention may be made without departing from its scope, it is intended that all matter contained in the above description shall be interpreted as 15 illustrative and not in a limiting sense.

I claim:

1. A decorative tying cord comprising a cord formed of a twisted strip of colored, flexible, non-fibrous regenerated cellulose and a flat, thin metallic strand wound about said core in open spirals.
2. A decorative tying cord comprising a core formed of a twisted strip of colored, plasticized, non-fibrous material and a flat, thin metallic strand spirally wound about said core in the same direction as the direction in which the core is twisted.
3. A decorative tying cord comprising a core formed of a twisted strip of flexible, non-fibrous material and a strand spirally wound about said

core, said strand comprising a narrow strip of flexible material having a metallic coating.

4. A decorative tying cord comprising a core formed of a twisted strip of flexible, non-fibrous material and a strand spirally wound about said 5 core, said strand comprising a strip of transparent, flexible, cellulosic material having a metallic coating.

5. A decorative tying cord comprising a core formed of a twisted strip of flexible, non-fibrous 10 material and a strand spirally wound about said core, said strand comprising a flat, thin strip of tinsel having rounded edges.

6. A decorative tying cord comprising a core formed of a twisted strip of flexible, non-fibrous 15 material and a strand spirally wound about said core in the same direction as the direction in which the core is twisted, said strand comprising a twisted flat, thin strip of tinsel.

7. A decorative tying cord comprising a core 20 formed of a twisted strip of flexible, non-fibrous material and a strand spirally wound about said core in open coils, said strand comprising an embossed flat, thin strip of tinsel.

8. A decorative tying cord comprising a core 25 formed of a twisted strip of flexible, non-fibrous material and a flat, thin metallic strand spirally wound about said core, said strand having a crinkled surface.

EDWARD PHILIP FRANKE. 30
